EMERGENCY GOVERNOR EXERCISER
Albert L. Cavalieri, Peabody, Mass., assignor to General Electric Company, a corporation of New York
Filed Mar. 28, 1960, Ser. No. 18,146
8 Claims. (Cl. 137—24)

This invention relates to an improved governing system for a prime mover such as a steam turbine, and more particularly it relates to an "exerciser" for the emergency governing mechanism which permits testing of all the emergency governing components while the turbine is operating without shutting down the turbine, including special means to automatically place the emergency governor back into an operative condition if the turbine overspeeds while the emergency governor is in a testing position.

A conventional steam turbine powerplant often includes both a "control" valve unit which is actuated by a "main" governor to control the flow of motive fluid to the turbine in accordance with the varying load demands, and also a "stop" valve which is actuated by an "emergency" governor to completely shut off the flow of motive fluid in case the turbine overspeeds. This invention is concerned with an "exerciser" mechanism for testing the emergency governing mechanism, since, although the emergency governing mechanism would rarely be called upon to function in actual service, reliability of its components is absolutely necessary. Inasmuch as the emergency governor has to be removed from operation for a short time in order to test it without shutting down the turbine, some "guarding" means must be provided to protect the turbine against overspeeding while the emergency governor is not operating. The eventuality of an overspeed condition while the emergency governing mechanism is being tested is quite serious and extensive damage could result to the powerplant if complete protection were not provided.

Patent 2,926,680, issued March 1, 1960, to Markus A. Eggenberger, and assigned to the assignee of the present application, describes a mechanism for testing the emergency governor without shutting down the turbine and includes an additional "pre-emergency" governor as a "guarding" means for shutting down the turbine in the event the turbine overspeeds during the period that the emergency overspeed governor is rendered ineffective. In that system, alternate control over the stop valve vests in either the main emergency governor or a "pre-emergency governor"; however, the pre-emergency governor or "guarding" means cannot be tested during operation.

The present invention overcomes the foregoing difficulties and provides an improved "exerciser" for an emergency governing mechanism in which every component can be tested while the turbine is operating.

Accordingly, one object of the present invention is to provide an improved emergency governing mechanism exerciser which permits testing of the emergency governor while the turbine is operating.

Another object is to provide a simplified arrangement for utilizing a speed responsive arrangement to "guard" the powerplant while the overspeed governor is being tested. A more specific object is to provide means for exercising all of the components of the emergency governing system, including the components of the "guarding" means itself, while the turbine is operating, while providing full overspeed protection at all times.

Other objects and advantages will become apparent from the following description taken in connection with the accompanying drawings in which:

FIG. 1 is a simplified schematic diagram illustrating the disposition of the emergency governor and the governor exerciser in relation to the overall powerplant;

2

FIG. 2 is a more detailed schematic diagram illustrating the various components of the emergency governor exerciser in the first phase of operation; and

FIG. 3 illustrates the emergency governor exerciser of FIG. 2 as it appears in the second phase of operation.

The invention, in one form, is practiced by providing a spill valve serving the hydraulically-operated valves, which is actuated by the emergency governor to shut down the powerplant. A special three-way valve is placed in the hydraulic line intermediate to the spill valve and the devices which it controls. The three-way valve normally resides in a "run" position and affords free communication between the spill valve and these devices, but when the emergency governor is to be exercised, the three-way valve is moved to a "test" position and bypasses the emergency governor-actuated spill valve. A "secondary governor" returns the three-way valve to its previous "run" position in the event that the turbine overspeeds while testing is taking place.

Referring now to FIG. 1 of the drawing, the emergency governor exerciser is shown in greatly simplified diagrammatic form so as to indicate its relationship with the powerplant and in order to illustrate the basic principle of operation. A prime mover such as a steam turbine 1 is furnished with motive fluid from the steam generating coils 2. A main governing mechanism 3 includes a flyball governor 4, a steam control valve 5, and an operating lever 6. The governing mechanism 3 regulates the speed of the turbine under varying load conditions in the conventional manner and the details are not pertinent to the present invention.

A stop valve 7 operated by hydraulic relay 8 is shown as a diagrammatic representation of typical equipment controlled by the emergency governor. A centrifugal pump 9 driven by turbine 1 furnishes hydraulic fluid under pressure to relay 8 through conduit 10. Hydraulic relay 8 is so constructed that the relay must be under hydraulic pressure furnished by the conduit 10, in order for it to hold stop valve 7 open. Loss of pressure in hydraulic line 10 will cause relay 8 to completely close stop valve 7 and shut off the flow of steam from the steam generator 2. Stop valve 7 is merely representative and it will be understood that many other devices may also be shut down or turned on by the emergency governor upon loss of pressure in line 10. Two examples would be the interstage valve in an extraction turbine or the reheat stop valve between two turbines where the motive fluid is reheated.

An emergency governor 11 is set to trip a spill valve 12 at a predetermined overspeed condition, for example, 110% of rated speed, discharging hydraulic fluid through drain conduit 13. A three-way valve 14 which is normally positioned to afford communication between spill valve 12 and hydraulic relay 8 is controlled by a speed responsive "secondary governor" 15. On desiring to test or "exercise" the system, a test signal from device 16 moves three-way valve 14 to bypass hydraulic fluid around spill valve 12 through the bypass line 17. Thus the emergency governor 11 can be tested and spill valve 12 actuated without losing pressure in line 10. The secondary governor 15, however, overrides the commands from test signal device 16 in the event that the turbine exceeds a predetermined speed while the emergency governor is being tested. Secondary governor 15 is a "guarding" device which returns three-way valve 14 to its previous running position when this speed is exceeded, to again put the emergency governor 11 in control. Thus the secondary governor 15 controls the ability of the emergency governor 11 to carry out its intended function.

With the above simplified explanation in mind, reference to FIG. 2 will show the actual emergency governor exerciser in more detail. Corresponding members in FIGS. 1, 2 and 3 bear the same numeral designations.

The emergency governor 11, which is of the "off-center bolt" type is geared to the turbine shaft in a suitable manner so as to turn therewith and includes an off-center member 11a held in retracted position by spring 11b to actuate a trip lever 20 at a predetermined speed in the conventional manner. An oil trip nozzle 21 set to discharge into the central portion 11c of emergency governor 11 is controlled by a valve 22. Thus the overspeed condition can be simulated by an opening valve 22 and discharging oil into the emergency governor 11 to trip lever 20 by creating an added eccentric load, even though governor 11 is turning at a speed less than the normal trip speed.

The foregoing overspeed simulating arrangement for testing the emergency governor 11 is disclosed in the aforementioned Eggenberger patent.

The spill valve shown generally at 12 comprises a pilot piston 12a biased downward by spring 12b and includes means for resetting piston 12a against the biasing of spring 12b by a lever 12c, link 12d, and a handle 12e in a manner which will be obvious from the drawing. Pilot piston 12a is held upward against the bias of spring 12b by a cam surface 20a on lever 20. In its "set" position, spill valve 12 affords a free flow of oil from a source of hydraulic pressure (not shown) by means of the conduit 23, ports 12f, 12g and conduit 24 to the three-way valve 14.

Three-way valve 14 is a fluid pressure actuated two-land piston-type valve which includes a housing 14a and a pressure actuated piston 14b. Hydraulic fluid from the same pressure source supplies three-way valve 14 through port 14c in the side of the housing via conduit 25 and port 14d in the end of the housing 14a via conduit 26. Surface 14e of the right-hand land defines a pressure chamber 14f with the valve housing 14a which biases the piston 14b to the left. A stop 14g prevents movement of the piston 14b to the left beyond a predetermined point. The surface 14h of the left-hand land defines with the casing 14a a pressure chamber 14i which is supplied with fluid by port 14j in the end of the housing. It will be observed that the area of surface 14h exposed to the pressure in chamber 14i is larger than that of surface 14e exposed to the pressure in chamber 14f. Therefore, if equal pressures exist in chambers 14i, 14f, piston 14b will be biased to the right.

Ports 14k, 14m in the side of housing 14a both communicate with a chamber 14n between the lands of the pilot piston when it is in its left-hand position, as shown in FIG. 2. Conduit 10 connects port 14k with the various devices controlled by the emergency governor mechanism and represented diagrammatically by the relay 8. Thus when the piston 14b is to the left ("run" position), relay 8 will be furnished with hydraulic fluid by way of conduit 23, spill valve 12, conduit 24, chamber 14n and conduit 10. Conversely, when piston 14b is in its right-hand position, relay 8 will be supplied with fluid by way of conduit 25, chamber 14n, conduit 10. Thus when piston 14b is to its right-hand position ("test" position), FIG. 3, spill valve 12 will be bypassed in order that governor 11 may be tested.

The secondary governor 15 controls the positioning of three-way valve 14. A two-land piston 15a is slideable in a housing 15b which defines ports 15c, 15d in the side of the housing. The top and bottom lands of pilot piston 15a define control orifices 15e, 15f with ports 15c, 15d respectively. Another port 15g between the lands communicates with port 14j of the three-way valve 14 by means of conduit 27. Hydraulic fluid is supplied to the secondary governor 15 through orifice 15e by way of conduit 28. A port 15h in the top of housing 15b and a branch conduit 29 connected to conduit 8 also allow entry of hydraulic fluid to a chamber 15i defined between the top land and the housing.

It will be apparent that the full top surface of the top land of piston 15a is exposed to the pressure in line 28.

Piston 15a is biased upward against the pressure in chamber 15i by a spring 15j disposed in a recess 15k in the bottom of housing 15b. A chamber 15m, defined between the lower side of the bottom land and the housing 5 aids spring 15j in biasing piston 15a upward. A constricted passageway 15p in the bottom land provides a pressure in chamber 15m which is equal to the pressure between lands. Thus a pressure reduction between lands (caused by closing orifice 15e and opening orifice 15f) is 10 transmitted by port 15p to chamber 15m. This improves the speed of response of piston 15a. A valve 30, having an effective area greater than that of port 15p, provides means to evacuate chamber 15m.

It will be apparent that piston 15a may be caused to 15 move downward in two different ways. First, by increasing the pressure in chamber 15i, the piston will begin to move, closing orifice 15e and opening orifice 15f. This causes the pressure between lands to drop off rapidly, and this loss of pressure is communicated to 15m to 20 further unstabilize piston 15a, causing it to move downward.

The second way to cause piston 15a to move downward is to open valve 30. The restricted opening 15p in the bottom land will not allow a rapid enough flow of hydraulic fluid to restore the full pressure in chamber 15m, 25 since the opening furnished by valve 30 is designed to be much greater than the restricted opening 15p.

The flow of hydraulic fluid to secondary governor 15 is controlled by a pilot valve 31 from a speed responsive 30 variable pressure source (not shown). This source may, for instance, be the centrifugal pump 9 shown in FIG. 1 whose outlet pressure varies as a function of turbine speed. The fluid enters through conduits 32, 33 and ports 31a, 31b respectively in valve housing 31c. A two-land piston 31d is slideable in housing 31c, and a port 31e 35 in the side of the housing communicates with a chamber 31f defined between the two lands and the housing. A port 31g leads to an exhaust conduit 31k and an additional port 31h leads to a chamber 31i defined beneath the bottom land and the housing. A source of hydraulic fluid under pressure (not shown) supplies fluid to port 31h and chamber 31i through a valve 34, and a connecting conduit 35. A restricted bleed orifice 36 is located 40 in communication with conduit 35 intermediate valve 34 and pilot valve 31. The upward pressure on the bottom land surface of piston 31d resulting from pressure in chamber 31i is opposed by pressure in an upper chamber 31j acting on the surface of the top land. It will be observed that the land surface area exposed to the pressure in chamber 31j is much smaller than the land surface area exposed to the pressure in chamber 31i so that the 45 position of piston 31d is at the top when the pressures in chambers 31j, 31i are equal. Chamber 31j is continuously exposed to the pressure in source conduit 33, whereas chamber 31i is exposed to the full hydraulic pressure only when valve 34 is opened. When valve 34 is closed, bleed orifice 36 slowly drains chamber 31i so that pilot valve piston 31d moves downward.

The top land of piston 31d of the pilot valve 31 defines 50 an orifice 31m with port 31a and the bottom land defines an orifice 31n with port 31g. As will be apparent from FIG. 2 of the drawing, when piston 31d is in its upward position, fluid is supplied from conduit 32 through orifice 31m, chamber 31f, port 31e, and conduit 28 to the secondary governor 15. Conversely, when pilot valve piston 31d is in its bottom position, orifice 31m is closed 55 and fluid can discharge from line 28 through port 31e, chamber 31f, orifice 31n, and out exhaust conduit 31k.

The hydraulic fluid supplying conduits 23, 25, 26, 35, 60 32, 33 may conveniently be from the same source. If the pressure of the fluid varies, orifices (not shown) may be used in conduits 23, 25, 26, 35 to obtain substantially constant pressure. However, it is necessary for the successful operation of exerciser governor 15 that the pressure of the hydraulic fluid furnished to conduits 32, 33

(hence to chamber 15*i*) vary as a function of the turbine speed. Since the main hydraulic oil pump 9 (see FIG. 1) is a centrifugal pump, the turbine hydraulic oil pressure will vary as the square of the turbine speed. Thus it is that the spring biased piston valve 15 is termed a "secondary governor," since it functions as a governor to trip the piston 15*a* when oil pressure is increased in chamber 15*i*. The greater the turbine speed, the greater the pressure in chamber 15*i* and the lower the piston 15*a* will move in its housing. The spring constant of spring 15*j* is selected to hold orifice 15*f* in a closed position when the turbine is at normal rated speed. When the speed of the turbine has increased to a predetermined amount, however, for example to 105% of rated speed, the pressure in chamber 15*i* supplied by the centrifugal turbine-driven pump has also increased to such an extent that orifice 15*f* starts to open. Thereafter, a rapid movement of piston 15*a* takes place.

The operation of my improved emergency governor exerciser will now be described. Referring to FIG. 2 of the drawing, the first phase of the governor exercising procedure is illustrated. Valve 34 is opened causing piston 31*d* of pilot valve 31 to rise to its top position as shown. Oil flows from conduit 32 through orifice 31*m*, chamber 31*f*, port 31*e*, conduit 28, and conduit 29 to chamber 15*i* on the top of the secondary governor piston 15*a*. Assuming that the turbine is not exceeding the calibrated overspeed setting of secondary governor 15 when testing is commenced, secondary governor piston 15*a* will remain close to the top of the housing and orifice 15*e* will remain open (shown closed in the drawing). The fluid entering through orifice 15*e* leaves the secondary governor 15 via port 15*g*, conduit 27, and enters chamber 14*i* of the three-way valve 14 biasing three-way valve piston 14*b* to the right or "test" position. In FIG. 2 of the drawing, the piston is shown to the left in its normal or "operating" position since it will be immediately returned to this position during the first phase of testing in the following manner.

Valve 30 is opened and fluid discharges from chamber 15*m* allowing piston 15*a* to move downward, opening orifice 15*f*. When this occurs, piston 14*b* of the three-way valve immediately returns to its "run" position as shown in FIG. 2, since the pressure in chamber 14*i* is relieved. Also, the secondary governor 15 has been simultaneously "exercised" by virtue of the movement of piston 15*a*. This gives the assurance that the piston 15*a* is not stuck or jammed and is free to operate smoothly.

It will be observed that a positive check of the speed calibration of secondary governor 15 is not obtained by thus exercising it by opening valve 30, but the only probable malfunction of secondary governor 15 would be due to plugged ports or sticking of the piston 15*a* in the housing. Thus merely causing the piston to move downward as though in an overspeed situation is a sufficient safety precaution.

It should be apparent that, during this first phase of testing, pilot valve 31, secondary governor 15, and three-way valve 14 have all been actuated thus insuring their reliable operation in case of an emergency. At the same time, it will be observed that the turbine has constantly been under surveillance by either the secondary governor 15 or by the emergency governor 11 during the foregoing. It is to be particularly noted that secondary governor 15 does not act to close any valves controlling motive fluid to the turbine, but that on the other hand it controls the ability of emergency governor 11 to function by means of its control over the three-way bypass valve 14.

Reference to FIG. 3 of the drawing will aid in an understanding of the operation of my emergency governor exerciser during the second phase of testing. Valves 30, 34 supplying the secondary governor 15 and the pilot valve 31 respectively are now closed. The bleed orifice 36 permits fluid to escape from the lower part of pilot valve 31 emptying chamber 31*i* and the pressure on the

top of the pilot piston 31*d* forces it downward. When this occurs, orifice 31*m* closes and orifice 31*n* opens allowing fluid to drain from the pressure chamber 15*i* at the top of the exerciser governor 15.

5 This resetting of the pilot valve 31 and the secondary governor 15 takes only a few seconds. Thereafter, valve 34 leading to pilot valve 31 is again opened and the piston 31*d* again rises to its uppermost position re-admitting hydraulic fluid to the chamber 15*i* of secondary governor 15. Fluid is also admitted through orifice 15*e* of the secondary governor to enter chamber 14*i* of the three-way valve and force the piston 14*b* of the three-way valve 14 to the right as shown in FIG. 3. This flow of fluid is a "test signal" since it sets valve 14 in its "test" position. Since the three-way valve 14 is in its "test" position, hydraulic fluid is bypassed from conduit 23 to the relay 8, and the emergency governor 11 may now be exercised without shutting down the turbine.

It is to be noted that while the subsequent testing 20 takes place, the turbine is under constant surveillance by secondary governor 15 and if the turbine overspeeds, the pressure in chamber 15*i* will increase, tripping piston 15*a* and discharging fluid from chamber 14*i* of three-way valve 14, thus returning it to its "run" position. In the 25 "run" position, of course, the emergency governor 11 has control and will shut off motive fluid to the turbine if its speed setting is exceeded.

The valve 22 supplying oil trip nozzle 21 is now opened and oil is admitted to the interior 11*c* of the governor 30 11. Its added weight moves the off-center member 11*a* outward to strike lever 20. When this occurs, cam surface 20*a* is rotated to allow the spring 12*b* of the spill valve 12 to force the spill valve piston 12*a* downward discharging the fluid in conduit 24. Note that the port 35 12*f* is also closed by the spill valve piston thus preventing loss of excessive fluid from the line 23. Valve 22 is then closed to stop oil from being admitted to 11*c*, which then resets 11*a*.

The operating capability of emergency governor 11 40 and spill valve 12 having been thus assured by exercising the components, spill valve 12 is reset by moving lever 12*e* to the left and the spring on lever 20 will re-establish the position of spill valve piston 12*a* on the cam surface 20*a*.

45 It only remains to close the valve 34 which permits pilot valve piston 31*d* to return to its bottom position. When this occurs, the three-way valve 14 is reset to its "run" position, with valve piston 14*b* moving to the left, the fluid in chamber 14*i* escaping via conduit 27, orifice 15*e*, conduit 28, orifice 31*n*, and discharge conduit 31*k*.

50 It will be understood that the explanation of the operation of the system referred to valves 22, 30, 34 as though they were manually operated. In actual practice, it is more convenient to employ electrical solenoid valves 55 operated in accordance with a predetermined switching sequence. The use of an electrically controlled sequence of operations with limit switches to determine the position of the various members assures that the proper sequence of valve openings and closings is carried out, 60 since the exercising of the emergency governing system must be a routine periodic inspection forming part of the safety plan of the power station. Also, a suitable time delay can be introduced between the switching events. The design of the circuitry to accomplish the 65 proper sequence of events lies within the scope of one skilled in the art, and is not included in the drawing since it would only tend to obscure the invention.

It also lies within the scope of the invention to use some other speed responsive means for a secondary governor, such as a flyball governor to position the three-way valve 14. The use of a hydraulic line pressure which varies as a function of turbine speed, however, is a convenient way to incorporate the speed responsive means into the system at a minimum cost and the reliability 75 of the pressure variation with speed is accurate enough

for guarding the turbine while the emergency governor is being exercised, since absolute accuracy of speed sensing is not necessary for this application. Hence, FIG. 1 of the drawing shows a general representation of the secondary governor indicating that other types of speed responsive means can be used to operate the three-way valve 14.

In conclusion, it will be seen that all components of the emergency exercising system are testable during operation without shutting down the powerplant. At the same time, full protection against the possibility of overspeed while the testing procedure is being carried out is provided by means of the arrangement described.

The importance of complete protection at all times cannot be overemphasized, since overspeed will cause serious damage to the powerplant. If the emergency governor were not periodically tested, long periods of idleness could possibly cause the valve pistons to stick in their housings. A routine "exercising" of all components will greatly reduce this possibility. The foregoing emergency governor exerciser provides a valuable adjunct to a safe, reliable powerplant and allows routine testing of the emergency governor without danger of overspeed possibility during testing.

It is, of course, intended to cover by the appended claims all such modifications as fall within the true spirit and scope of the invention.

What I claim as new and desire to secure by Letters Patent of the United States is:

1. In combination a turbine having inlet valve means controlling the flow of motive fluid to the turbine, fluid pressure actuated motor means connected to operate the inlet valve means, a source of actuating fluid under pressure supplying said motor means, emergency governor means responsive to a first turbine overspeed condition, means to artificially trip said emergency governor means at a speed below said first turbine overspeed, an emergency governor exerciser for said turbine comprising first means operated by the emergency governor means controlling the flow of actuating fluid to the motor means, second means having a "run" position bypassing fluid between said first means and said motor means and a "test" position controlling the flow of actuating fluid to the motor means independently of said first means, whereby the emergency governor and the first means may be tested without shutting down the turbine, third means to place said second means in the "test" position, and secondary governor means responsive to a second turbine overspeed condition adapted to inactivate said third means by returning said second means to the "run" position when the second turbine overspeed is exceeded, whereby primary control over the motor means will be returned to the first means.

2. The combination according to claim 1 and including means to artificially actuate the secondary governor means at a speed below the second turbine overspeed, whereby it will also inactivate said third means.

3. In combination a turbine having inlet valve means controlling the flow of motive fluid to the turbine, fluid pressure actuated motor means connected to operate the inlet valve means, a source of actuating fluid under pressure supplying said motor means, spill valve means connected to discharge actuating fluid from said motor means, emergency governor means responsive to a first turbine overspeed condition to actuate said spill valve means, means to artificially trip said emergency governor means below said first turbine overspeed, an emergency governor exerciser for said turbine comprising three-way valve means having a first position connecting the spill valve means directly with the motor means and a second position connecting the actuating fluid source with the motor means and bypassing the spill valve means, whereby the emergency governor means may be artificially tripped below the first turbine overspeed when the three-way valve means is in the second position without shutting

down the turbine, and secondary governor means responsive to a second turbine overspeed condition connected to return the three-way valve means to its first position in the event that the second turbine overspeed is exceeded while the emergency governor is being tested.

4. In combination a turbine having inlet valve means controlling the flow of motive fluid to the turbine, fluid pressure actuated motor means connected to operate the inlet valve means, a first source of actuating fluid under pressure supplying said motor means, spill valve means connected to discharge actuating fluid from said motor means, emergency governor means responsive to a first turbine overspeed condition to actuate said spill valve means, means to artificially trip said emergency governor means below said first turbine overspeed, an emergency governor exerciser for said turbine comprising three-way valve means having a first position connecting the spill valve means directly with the motor means and a second position connecting the actuating fluid source with the motor means and bypassing the spill valve means, whereby the emergency governor means may be artificially tripped below the first turbine overspeed when the three-way valve means is in the second position without shutting down the turbine, secondary governor means responsive to a second turbine overspeed condition connected to return the three-way valve means to its first position in the event that the second turbine overspeed is exceeded, and means to artificially actuate said secondary governor means below the second turbine overspeed, whereby it will simultaneously move the three-way valve means from its second position to its first position while said secondary governor is being actuated.

5. In combination a turbine having inlet valve means controlling the flow of motive fluid to the turbine, fluid pressure actuated motor means connected to operate the inlet valve means, a source of actuating fluid under pressure supplying said motor means, spill valve means connected to discharge actuating fluid from said motor means, emergency governor means responsive to a first turbine overspeed condition to actuate said spill valve means, means to artificially trip said emergency governor means below said first turbine overspeed, an emergency governor exerciser for said turbine comprising three-way valve means having a first position connecting the spill valve means directly with the motor means and a second position connecting the actuating fluid source with the motor means and bypassing the spill valve means, whereby the emergency governor means may be artificially tripped below the first turbine overspeed when the three-way valve means is in the second position without shutting down the turbine, a second source of actuating fluid having a pressure varying as a function of turbine speed, secondary governor means including a housing having biased piston means therein with a surface exposed to said second actuating fluid pressure source and connected to return the three-way valve means to its first position in the event that the second turbine overspeed is exceeded while the emergency governor is being tested.

6. In combination a turbine having inlet valve means controlling the flow of motive fluid to the turbine, first fluid pressure actuated motor means connected to operate the inlet valve means, a first source of actuating fluid under pressure supplying said motor means, spill valve means connected to discharge actuating fluid from said first motor means, emergency governor means responsive to a first turbine overspeed condition to actuate said spill valve means, means to artificially trip said emergency governor means below said first turbine overspeed, an emergency governor exerciser for said turbine comprising three-way valve means including a housing having slidable piston means therein exposing a first pair of ports in a first position connecting the spill valve means with the motor means and exposing a second pair of ports in a second position connecting the first actuating fluid source with the first motor means, second fluid

pressure actuated motor means arranged to move the three-way valve piston toward the second position, means to bias the piston toward its first position, a second source of actuating fluid under pressure supplying said second motor means, and secondary governor means responsive to a second turbine overspeed condition and connected to discharge fluid from said second motor means when the turbine exceeds said second turbine overspeed, whereby the three-way valve piston will be returned to its first position in the event that the second turbine overspeed is exceeded while the emergency governor is being tested.

7. In combination a turbine having inlet valve means controlling the flow of motive fluid to the turbine, fluid pressure actuated motor means connected to operate the inlet valve means, a first source of actuating fluid under pressure supplying said motor means, spill valve means connected to discharge actuating fluid from said motor means, emergency governor means responsive to a first turbine overspeed condition to actuate said spill valve means, means to artificially trip said emergency governor means below said first turbine overspeed, an emergency governor exerciser for said turbine comprising three-way valve means including a housing having slidable piston means therein exposing a first pair of ports in a first position connecting the spill valve means with the motor means and a second pair of ports in a second position connecting the first actuating fluid source with the motor means and bypassing the spill valve means, whereby the emergency governor means may be tripped when the three-way valve is in the second position without shutting down the turbine, said three-way valve means housing also defining together with the piston a first pressure chamber to move the piston toward its second position,

means to bias the three-way valve piston toward its first position, a second source of actuating fluid having a pressure varying as a function of turbine speed, pilot valve means connected to control the flow from said second pressure source, secondary governor means including a housing having slidable piston means therein, exposing a third pair of ports in a third position connecting said pilot valve means with said three-way valve first pressure chamber and a fourth pair of ports in a fourth position arranged to discharge fluid from the first pressure chamber, resilient means biasing the secondary governor piston toward its third position, the exerciser governor piston also defining together with its housing a second pressure chamber opposing said resilient means and connected to said pilot valve means, whereby increase in pressure of the second source of actuating fluid beyond that corresponding to a predetermined second turbine overspeed condition will move the secondary governor piston from its third position to its fourth position to discharge fluid from the first pressure chamber of the three-way valve means in the event the second turbine overspeed is exceeded while the emergency governor means is being tested.

8. The combination according to claim 7 and including means to artificially actuate the secondary governor means below the second turbine overspeed, whereby it will simultaneously move the three-way valve means from its second position to its first position while the secondary governor means is being actuated.
